(57) **CLAIM**

I claim the ornamental design for the decision making device, as shown and described.

DESCRIPTION

FIG. 1 is a top perspective view of a decision making device; FIG. 2 is a bottom perspective view of the decision making device;

FIG. 3 is a front elevational view thereof.

FIG. 4 is a right-side elevational view thereof.

FIG. 5 is a left-side elevational view thereof.

FIG. 6 is a rear elevational view thereof.

FIG. 7 is a top plan view thereof; and,

FIG. 8 a bottom plan view thereof.

The broken line showings on the drawings is included for the purpose of illustrating and forms no part of the claimed design.
